F. B. SWISHER

SCISSORS SHARPENER

Filed Oct. 21, 1922

Inventor
Frank B. Swisher
By his Attorney, A. de Bonneville

UNITED STATES PATENT OFFICE.

FRANK B. SWISHER, OF NEW YORK, N. Y., ASSIGNOR TO ELLIS M. POTTER, OF NEW YORK, N. Y.

SCISSORS SHARPENER.

Application filed October 21, 1922. Serial No. 596,089.

To all whom it may concern:

Be it known that I, FRANK B. SWISHER, a citizen of the United States, and resident of the borough of Manhattan, city of New York, in the county of New York and State of New York, have invented certain new and useful Improvements in Scissors Sharpeners, of which the following is a specification.

10 This invention relates to a scissors sharpener. Its object is the production of a scissors sharpener that is light in weight, simple in construction, and adapted to quickly sharpen the blades of a pair of

15 scissors.

The organization of the invention comprises a cutting element consisting of a rod of hardened steel that has mounted on its opposite ends, a pair of light spherical supports.

20 The accompanying drawing exemplifies one form of the sharpener. It comprises the cylindrical sharpening rod 10 of hardened steel, that has connected to its ends, in this instance, the wooden balls 12.

25 To use the sharpener, the balls 12 are held with thumb and forefinger of the user, and the blades of a pair of scissors to be sharp-

ened are opened and located with their heels bearing on the rod 10, and then drawn 30 toward their points, bearing on said rod. This operation is repeated a few times and the blades are thereby sharpened.

It is to be understood that various modifications can be made in the invention without departing from the spirit thereof, and the present exemplification is to be taken as illustrative and not limitative of the invention.

Having described my invention, what I 40 desire to secure by Letters Patent and claim is:

1. In a sharpener of the character described the combination of a cylindrical sharpening rod and a pair of spherical supports on the ends of the rod.

2. In a sharpener of the character described the combination of a hardened steel cylindrical rod and a pair of wooden spherical supports on the ends of the rod.

Signed at the borough of Manhattan, city of New York, in the county of New York and State of New York, this 9th day of October A. D. 1922.

FRANK B. SWISHER.
